Attest.

UNITED STATES PATENT OFFICE.

WALTER G. VREELAND, OF CHATTANOOGA, TENNESSEE, ASSIGNOR TO LUCEY MANUFACTURING CORPORATION OF TENNESSEE, OF CHATTANOOGA, TENNESSEE, A CORPORATION OF TENNESSEE.

CROWN-BLOCK FOR WELL-DRILLING APPARATUS.

1,368,775.

Specification of Letters Patent. Patented Feb. 15, 1921.

Application filed September 15, 1919. Serial No. 323,727.

To all whom it may concern:

Be it known that I, WALTER G. VREELAND, a citizen of the United States, residing at Chattanooga, in the county of Hamilton and State of Tennessee, have invented certain new and useful Improvements in Crown-Blocks for Well-Drilling Apparatus; and I do declare the following to be a full, clear, and exact description of the invention, such as will enable others skilled in the art to which it appertains to make and use the same, reference being had to the accompanying drawings, and to the letters and figures of reference marked thereon, which 15 form a part of this specification.

My invention relates to crown blocks for oil derricks. It has for its primary object to provide an improved construction for spacing apart and clamping together and 20 bracing the beams which support the shafts on which the sheaves are mounted; and also to provide an improved construction of sheave and shaft on which the same is mounted and manner of holding the sheave 25 shaft in position on the beams. To the accomplishment of the foregoing and such other objects as may hereinafter appear the invention consists in the features hereinafter described and then sought to be clearly defined by the claims, reference being had to the accompanying drawing forming a part hereof and in which—

Figure 1 is a plan view of a crown block constructed in accordance with the present 35 invention, a seven pulley crown block being selected for purposes of illustration;

Fig. 2 is a side view of Fig. 1, one of the sheave hubs and shaft being sectioned to show the oiling means;

Fig. 3 is an end view of the crown block, 40 one of the sheaves and its shaft and its supporting beams being in section.

In the drawing the beams 1 of the crown-block are five in number and formed of I 45 metal bars or beams with two of the beams extended forward of the others to receive the sand line sheave as illustrated. The beams are spaced apart by spacer-frames 2 inserted between the beams at their ends so 50 that the corners of the frames will fit in the angles of the webs and flanges of the beams as shown in Fig. 3, the beams and spacer-frames being tied together by double-headed bolts 3 passed through the beams and spacer-

frames. The spacer-frames form a quadrangular brace between the beams at their ends and having their corners fitting in the angles between the webs and flanges of the beams and secured by relatively long double-headed bolts to the beams, a very strong, 55 stable and braced structure is formed.

On top of the I beams rest the shafts which support the sand-line sheave 5, the casing sheaves 6 and the drilling line sheave 7. As each of these shafts has the same features of construction and is attached to the beams in the same manner, the same designating reference numeral will be used for each. The shafts are designated by the numerals 8. Each shaft is cored with a central hole 9, and at the ends with angularly disposed holes 10 designed to receive the angularly disposed hook-bolts 11 which will secure the shafts to the I beams, the lower portions of the holes 10 being square or angular in cross section to prevent the hook-bolts 11 from turning as their nuts are tightened. The shafts are formed with a centrally enlarged portion 12 which will be machined to receive the sheave and its bushing, and 70 the under faces of the shafts will preferably be flattened so as to seat firmly on the top of the beams, and the under portion of the enlargement 12 forms at each end thereof a shoulder 13 against which will abut the inner edges of the top flanges of the I beams 75 on which the shafts rest. When the shafts are formed and fitted as described and the angularly disposed hook-bolts are applied with their hook ends gripping the flanges of 80 the I beams and their nuts 14 are tightened up the bolts will tend to draw on or pull the beams one toward the other with the edges of the top flanges of the beams bearing 85 against the shoulders on the shafts so that any shock transmitted to one beam or any tendency of one beam to buckle is transferred to and resisted by the other beam on 90 which the shaft rests. Under this construction all the beams of the crown-block are tied 95 together by means of the sheave or pulley shafts and their attaching hook-bolts as well as by the spacing-frames and their securing bolts at opposite ends of the beams and thus a very strong and durable structure is provided. When the nuts of the hook-bolts are 100 loosened the sheave and its shaft may be positioned in the I beams and then securely 105

locked or clamped in position by tightening the nuts on the bolts.

Each pulley or sheave is formed with a hollow hub 15 divided by a central partition 16 with communicating parts 17 and is provided with a bronze bushing 18 to fit the machined enlargement of the shaft. The bushing is formed with recesses or transverse openings 19 to receive a fibrous material 20 which will bear against the machined enlargement of the shaft and receive oil from the hollow hub of the sheave to which the oil may be supplied through a capped opening 21 so as to lubricate the bearing surface between the bushing and its shaft.

I have illustrated and described the preferred details of construction of the various parts but it is to be understood that changes may be made therein and essential features of the invention retained.

Having described my invention and set forth its merits what I claim is:

1. A crown-block comprising parallel beams, a sheave sustaining shaft resting upon the beams and formed with shoulders constituting abutments for portions of the beams, and bolts extending angularly in opposite directions through the sheave sustaining shaft and engaging upper side portions of the beams, and means for tightening the bolts to tie together the shaft and beams.

2. A crown-block comprising parallel beams, a sheave sustaining shaft resting upon the beams, said shaft being formed with bolt openings extending angularly in opposite directions through the shaft, a portion of the openings being angular in cross section, hook-bolts passing through said openings and having their hooks engaging upper side portions of the beams, and means for tightening the bolts to tie the shaft and beams together.

3. A crown-block comprising parallel flanged beams, a spacing frame between the beams with the corners of the frame fitting

in the angle of the webs and flanges of the beams to form a quadrangular brace, and tie bolts passing through the beams and spacing-frame for tying the frame and beams together and prevent movement of the quadrangular brace.

4. A crown-block comprising parallel flanged beams, a spacing-frame between the beams, bolts passing through the beams and frame for tying the same together, a sheave sustaining shaft resting upon the beams and having a shoulder constituting an abutment for the flanged portion of the beams, and bolts passing angularly in opposite directions through said shaft and held in clamping engagement with the upper flanged portion of the beam.

5. A crown-block comprising parallel flanged beams, a spacing-frame between the beams, bolts passing through the beams and frame for tying the same together, a sheave sustaining shaft resting upon the beams, and bolts passing angularly in opposite directions through said shaft and held in clamping engagement with the upper portions of the beams and serving to tie the shaft and beams together.

6. A crown-block comprising parallel flanged beams, a sheave sustaining shaft resting upon the beams and formed with a centrally enlarged portion, a sheave formed with a hollow hub and internal bushing fitted to the enlarged central portion of the shaft, and bolts passing angularly in opposite directions through the shaft and having clamping engagement with the upper flanges of the beam to draw the enlarged portion of the shaft and the flanges of the beam one toward the other.

In testimony whereof I affix my signature in presence of two witnesses.

WALTER G. VREELAND
